(57) **CLAIM**

The ornamental design for a coffee distribution tool, as
shown and described.

DESCRIPTION

FIG. 1 is a front and top perspective view of a coffee
distribution tool, showing my new design;

FIG. 2 is a rear and bottom perspective view thereof;

FIG. 3 is an exploded view thereof;

FIG. 4 is a front and top perspective view of the bottom
portion of the coffee distribution tool, shown separately to
show aspects of the design that are not visible when combined;

FIG. 5 is a rear and bottom perspective view thereof;

FIG. 6 is a front elevation view thereof;

FIG. 7 is a rear elevation view thereof;

FIG. 8 is a left side elevation view thereof;

FIG. 9 is a right side elevation view thereof;

FIG. 10 is a top plan view thereof;

FIG. 11 is a bottom plan view thereof;

FIG. 12 is a front and top perspective view of the top portion
of the coffee distribution tool, shown separately to show
aspects of the design that are not visible when combined;

FIG. 13 is a rear and bottom perspective view thereof;

FIG. 14 is a front elevation view thereof;

FIG. 15 is a rear elevation view thereof;

FIG. 16 is a left side elevation view thereof;

FIG. 17 is a right side elevation view thereof;

FIG. 18 is a top plan view thereof; and,

FIG. 19 is a bottom plan view thereof.

The broken lines in the figures illustrate portions of the
coffee distribution tool that form no part of the claimed
design.
